(57) **CLAIM**

The ornamental design for a cleaning pad, as shown and described.

DESCRIPTION

FIG. 1 is a perspective view of the cleaning pad of my new design.

FIG. 2 is a top plan view thereof.

FIG. 3 is a bottom plan view thereof.

FIG. 4 is an elevational view of one side thereof.

FIG. 5 is an elevational view of the opposite side thereof.

FIG. 6 is an elevational view of the forward end thereof; and, FIG. 7 is an elevational view of the rear end thereof.

The broken lines of FIG. 1, showing a foot, represent environmental background elements and form no part of my new design.

1 Claim, 5 Drawing Sheets
